UNITED STATES PATENT OFFICE.

PATRICK P. LA MONTAGNE, OF BOURBONNAIS, ILLINOIS, ASSIGNOR TO PARAMOUNT KNITTING COMPANY, OF CHICAGO, ILLINOIS, A CORPORATION OF ILLINOIS.

KNITTING-MACHINE NEEDLE.

1,339,959.

Specification of Letters Patent. Patented May 11, 1920.

Application filed March 13, 1918. Serial No. 222,057.

To all whom it may concern:

Be it known that I, PATRICK P. LA MONTAGNE, a citizen of the United States, residing at Bourbonnais, county of Kankakee, 5 State of Illinois, have invented an Improvement in Knitting-Machine Needles, of which the following description, in connection with the accompanying drawing, is a specification, like characters on the drawing representing like parts.

This invention relates to a knitting machine and particularly to the needle. The needle is of the type in which the hook member and latch member are separate members, that is, physically independent and 15 separate from each other although co-acting to perform the required looping functions.

It is the object of the invention to provide a needle of this type which may be mounted and operate in the usual needle slot of the dial bed, cylinder bed or other 20 needle bed and thus obviate the necessity of an additional separate slot for the latch 25 member frequently employed in connection with this type of needle. This feature of the invention enables the separate latch type of needle to be employed in existing knitting machines without alteration of the 30 needle bed and it also eliminates the necessity of re-designing knitting machines so as to enable them to be provided with the additional slot for the latch member.

It is the object of the invention also to 35 provide a latch member which may be manufactured expeditiously and inexpensively and which shall present a simple and efficient means for effecting the necessary retarding friction with the side walls of the 40 needle slot.

It is the object of the invention also to 45 provide a construction of latch member which when effecting the said necessary retarding friction shall be readily insertible with the hook member in the slot in the bed.

It is the object of the invention also to 50 provide a needle of this type in which the latch member moves within the boundaries of the hook member and is provided with a pointed head projecting through a longitudinal slot in the hook member to enable the point of the latch to move into and out of co-operative relation with the hook.

These and other objects of the invention 55 will appear more fully from the accom-

panying description and drawings and will be particularly pointed out in the claims.

The drawings represent so much of a knitting machine as is necessary for a disclosure of the invention.

60

In the drawings,

Figure 1 is a central vertical cross section of a portion of the dial of an ordinary type of knitting machine with the preferred form of needles embodying the invention in 65 position therein;

Fig. 2 is a side elevation of a preferred form of needle with the hook member shown in longitudinal cross section and with the parts in casting off position;

70

Fig. 3 is a view similar to Fig. 2 but with the members shown in forward projected or yarn-receiving position;

Fig. 4 is a bottom plan view of the needle with the members in the position shown in 75 Fig. 2;

Fig. 5 is a development of the latch member;

Fig. 6 is a perspective view of the latch member shown in the preceding figures;

80

Fig. 7 is a view in vertical cross section of a portion of a needle cylinder with a needle embodying the present invention adapted for use therein.

The present invention presents a knitting 85 machine needle particularly valuable for use in the dial where the problems arising from the limitations of space and of restriction of movement are more difficult, but the main principles of the invention are 90 equally applicable to the cylinder needle and both forms are herein illustrated. This invention shortens the length over all required for the needle and its longitudinal movement and thus, in the case of the dial 95 of a circular knitting machine, enables a smaller dial to be employed or a greater number of needles to be employed in a dial of a given size, thus in turn enabling a finer quality of work to be performed.

100

The features of the invention will best be understood by an examination of a preferred form of construction embodying the invention such as herein illustrated.

The invention is adapted for use in any 105 ordinary type of knitting machine. In Fig. 1 the bed 1 of the dial of an ordinary type of circular knitting machine is shown supported on the vertical stud or shaft 2 and this bed is provided with the usual radial 110

needle-receiving and guiding slots 3. The usual cam groove 4 is shown, formed between the cam members 5 and 6, for operating the butts of the needle to give the necessary movements thereto.

In this type of needle one member is given a reciprocating movement and the other member obtains its movements from the first member. In the construction illustrated the 10 hook member is provided with a butt coöperating with the cam groove 4 by means of which the hook member is positively moved in and out or back and forth and the latch member receives its movement from the 15 hook member.

The hook member 7 in the construction shown in Figs. 1 to 4 inclusive presents at its forward end the hook proper 8 which at the outer face of the tip is provided with a 20 groove 9 adapted to receive the latch point. This hook member is also provided with a longitudinal transverse slot 10 extending through the body of the hook member adjacent the hook. The hook member is also 25 provided with the usual butt 11 by which it is operated from the cam groove 4. The hook member is provided with a lateral opening preferably in the form of a recess 12 at its rear face formed in the shank 30 thereof and preferably by a stamping or punching operation so as to leave sharply and accurately defined shoulders 13 and 14. The slot 10 opens into this recess.

The hook member may be formed by any 35 suitable method of manufacture but preferably the body of the hook member is punched out so that the hook member may present an accurately positioned and sharply defined butt and accurately positioned and 40 sharply defined shoulders 13 and 14. The longitudinal slot 10 may be and usually is formed by a sawing operation. For this purpose two thin circular saws 15 and 16 may be employed. The saw 15 travels along 45 the path 17 cutting the groove 9 in the hook tip and the straight rear or bottom wall 18 and the slot 10 until it comes closely adjacent to the butt 11 as indicated in Fig. 3. The cutting of the slot 10 is then completed 50 by the saw 16 which is moved in from the rear to the position indicated in Fig. 3.

The latch member separately shown developed in Fig. 5 and completed in Fig. 6 is preferably formed of thin sheet metal 55 stamped out and then bent to the required shape.

This latch member comprises a head 19 provided with a point 20 adapted to coöperate with the tip of the hook, the point 20 60 when the needle is retracted lying over the groove 9. The shank 21 of the latch has a portion thereof 22 extended transversely from the main body of the shank and then bent back parallel to itself so that the shank 65 presents a U-shaped resilient section. The

forward portion of the shank is then bent to bring it into the central longitudinal plane of the U-shaped section. A notch 23 is formed in the portion 22 so that when the portion 22 is bent into U-shaped form the 70 forward edge or shoulder 24 will align transversely with, or be slightly forward of, the shoulder 25 formed by the bend in the shank to bring the shank into central alinement. This U-shaped section is so formed that its 75 total width is somewhat greater than the width of, or the distance between the side walls of, the needle slot so that when the latch member is in position in the needle slot the resiliency of this U-shaped section will 80 cause a frictional retarding action between the latch member and the walls of the needle slot. The ends of the U-shaped section are bent or pinched toward each other sufficiently to bring them within the boundaries 85 of the side walls of the hook member, thus enabling the hook member with the contained latch readily to be slipped into the needle bed groove or slot.

The proportions of the latch member with 90 respect to the hook member are such that the latch member lies entirely within the boundaries of the hook member, the head lying 95 in the slot 10 and the U-shaped section fitting snugly into the recess 12 with the rear of the latch member against the bottom wall of the needle slot. The distance between the shoulders 13 and 14 of the hook member and the length of the U-shaped portion of the latch member are relatively such 100 that when the hook member is reciprocated the proper movement and coöperative action of the latch member is secured.

The needle is shown in retracted position in Fig. 2. The cam groove 4 acting on the 105 butt 11 projects the hook member outwardly until the shoulder 14 comes into contact with the shoulder 26 at the end of the U-shaped section. During this movement of the hook member the latch member remains longitudinally stationary owing to the engagement of the U-shaped section with the walls 110 of the needle slot and the hook is uncovered. During this movement the latch member rocks slightly transversely as the head 19 115 rides down on the wall 18. When the shoulder 14 contacts with the shoulder 26 of the latch member, as shown in Fig. 3, the point of the latch extends forward of the shoulder 13, thus preventing the latch point from 120 passing behind the hook member, and the latch member is then carried bodily forward 125 until both members reach the required projected or yarn-receiving position. The yarn is then fed to the hook. The cam then acts to retract the hook member. During this re- 130 tracting movement the latch member is again held longitudinally stationary by reason of the frictional engagement of the U-shaped section with the walls of the needle 135

slot until the shoulder 13 comes into contact with the shoulder 24 or shoulders 24 and 25 at the opposite end of the U-shaped section of the latch member and during this 5 movement the head 19 of the latch member rides up on the wall 18 and lies over the groove 9 in the hook 8. Then as the retracting movement continues both members of the needle move together and the loop of 10 the preceding stitch is cast off.

The entire needle is thus made very compact. The tendency to rock the needle bodily caused by the action of the cam on the butt is at the minimum because both the body of 15 the latch member and the body of the hook member are as close to the point at which the butt is engaged by the cam as is possible so that the rocking movement is minimized.

When the latch member is in its forward 20 position with its point resting in the groove 9 of the hook tip, the head of the latch member rests upon, and is supported by, the forward inclined wall 18 of the slot in the hook member so that the point of the latch member 25 is bridged across the opening of the hook and thus supports the yarn in the casting off operation so as to bring the minimum amount of strain upon the needle. The point 30 of the latch resting over the groove 9 in the hook tip also causes the needle to present the minimum cross sectional area thus bringing as little strain as possible upon the work in the knitting operation. This groove 9 enables the point of the latch normally to 35 stand closer to the hook tip without touching the hook tip and insures the point of the latch seating in the groove and centrally of the hook when drawn toward the hook by sufficient strain from the yarn.

40 The latch member shank being held between the front wall of the recess 12 of the hook member and the bottom of the needle slot prevents the rear end of the latch member from moving bodily transversely with 45 respect to the hook member and insures the maintenance of the relative longitudinal movement of the needle members.

The adaptation of the principles of this 50 invention to the cylinder needle is apparent and is illustrated in Fig. 7 wherein a portion of a needle cylinder 27 is shown provided with the needle slot 28. The hook member 29 of the needle has the usual elongated shank provided with the butt 30 operated by the cam 31. The only difference 55 between this needle and that already described is that the shank of the hook member is prolonged beyond the recess 32, corresponding to the recess 12 already described, 60 and the butt is transferred to the usual position for a cylinder needle. The operation of the needle is the same as that already described.

It will thus be seen that all the objects of 65 the invention hereinbefore set forth are at-

tained in the forms of needle herein described and illustrated as the preferred forms of the invention. These needles are readily and inexpensively manufactured and the coöperating parts are preferably formed 70 by punching or stamping operations enabling the interengaging portions of the members to be positioned and defined with extreme accuracy so that the relative movements and positions of the needle members may be 75 given and secured with extreme accuracy.

The needle presents a self-contained structure which may be readily inserted in the slots of the ordinary types of knitting machines without requiring any alteration or 80 redesigning thereof.

Having fully described my invention, what I claim as new and desire to secure by Letters Patent is:

1. A knitting machine needle comprising 85 a longitudinally slotted hook member and a separate latch member, means for effecting the longitudinal reciprocation of the one member from the other, the said hook member being provided with a lateral opening 90 communicating with said slot, the said latch member when in retracted position being located entirely in said opening and slot with the head of the latch member movable relatively to the hook member through said slot 95 to bring the point of the latch member into and out of coöperation with the hook.

2. A knitting machine needle comprising a longitudinally slotted hook member and a separate latch member having a section of 100 its shank laterally resilient and of greater width than the width of the needle bed slot in which the needle is to operate, the said hook member being provided with a lateral opening, the said latch member being located within the boundaries of the hook member with the resilient section thereof in said opening and with its head movable through said slot to bring the point thereof into and out of coöperation with the hook 110 when the hook member is reciprocated longitudinally.

3. A knitting machine needle comprising a longitudinally slotted hook member provided with a shouldered recess at its back, 115 a separate latch member located within the boundaries of said hook member having a head movable through said slot to bring the point thereof into and out of coöperation with the hook and having a portion of its 120 shank extended transversely and bent back parallel to itself to form a U-shaped resilient section of greater width than the width of the hook member and located within said recess.

4. A knitting machine needle having the construction specified in claim 3 in which the said U-shaped section is pinched or bent together at its ends to bring the ends within 130 the side walls of the hook member and thus

enable the needle readily to be slipped into a slot of a needle bed.

5. A latch member for a separate latch knitting machine needle having a point for coöperating with the hook of the needle and having a shank, a portion of the shank being extended transversely and bent back parallel to itself to form a U-shaped resilient section adapted for frictional engagement with the 10 side walls of a needle guiding slot.

6. A latch member for a separate latch knitting machine needle having the construction specified in claim 5 in which the body of the shank extends in the central 15 longitudinal plane of the said U-shaped section.

7. A latch member for a separate latch knitting machine needle having a point for coöperating with the hook of the needle and 20 having a shank, a portion of the shank being extended transversely and provided with a notch adjacent the shank, the said portion being bent back parallel to itself to form a U-shaped resilient section adapted for fric-

tional engagement with the side walls of a 25 needle guiding slot, the body of the shank extending in the central longitudinal plane of the said U-shaped section, and the said notch permitting the forward edge of the said extended portion when bent back to 30 align with or extend forward of the shoulder formed at the bend of the shank to bring it into said central plane.

8. A knitting machine needle comprising a longitudinally slotted hook member, a 35 separate latch member provided with a shank and with a head passing through the slot of the hook member, the latch member being located within the boundaries of the hook member whereby the entire needle may 40 be mounted in a single needle bed slot, the said latch member comprising laterally resilient means adapted to engage the side walls of the needle slot.

In testimony whereof, I have signed my 45 name to this specification.

PATRICK P. LA MONTAGNE.
